UNITED STATES PATENT OFFICE.

HENRY MARLES, OF LONDON, ENGLAND.

STEERING GEAR.

Application filed January 25, 1922, Serial No. 531,790, and in Great Britain May 18, 1921.

This invention relates to improvements in steering gears for mechanically propelled vehicles, and is more particularly directed to the type of steering gear disclosed 5 in my co-pending application filed October 9, 1920, Serial No. 415,927, wherein radially extending cams mounted on the lower end of the steering column cooperate with a roller carried by the rocker shaft.

10 The primary object of this invention is to provide a small and economical gear, which will be of extremely strong and rugged construction, and wherein means are provided that can be conveniently adjusted for 15 taking up any wear that may occur between the contacting surfaces, thereby eliminating back lash in the steering mechanism.

The invention will be best understood from a consideration of the following detailed description taken in connection with the 20 accompanying drawing forming part of this specification, with the understanding, however, that the invention is not confined to any strict conformity with the 25 showing in the drawing, but may be changed and modified so long as such changes and modifications mark no material departure from the salient features of the invention as expressed in the appended 30 claims.

In the drawings:—

Fig. 1 is a side elevation of an illustrative embodiment of the invention.

Fig. 2 is a vertical section of the same.

35 Fig. 3 discloses another angular position of the rotatable disk shown in Fig. 2.

Fig. 4 is a section taken along the line 4—4 of Fig. 1, disclosing partly in section a means for adjusting the roller disk.

40 Fig. 5 is a fragmentary view of the same, showing another position of the roller disk which is in operative engagement with the rocker shaft and the cams, disclosing a modified form of adjustment means for the 45 roller disk.

Fig. 6 shows a modified form of disk operatively positioned between the rock shaft and the opposed cam tracks.

50 Fig. 7 discloses another modification of the disk located at a different angle and engaged by different portions of the cam tracks.

Referring to the drawing, 1 indicates a

shaft provided with a keyway 2. The shaft is disposed in alignment with the end of the 55 steering column of an automobile, and is adapted to be connected in operative relation with said column and rotated therewith, when the steering wheel is operated. A sleeve (not shown) on the steering column 60 may be provided with a keyway aligned with the keyway 2 and engaged by a key for locking the shaft to the steering column. The shaft 1 may also be considered as the 65 lower end of the steering column itself.

A casing 4 is mounted on the end of the steering column and encloses the shaft 1, the cam 3 and the parts operatively connected with said cam. The casing, as is usually the case, is sectionally formed and 70 bolted together in order that the enclosed mechanism may be exposed for any purpose whatever.

Extending at an angle to the shaft 1 and to the main body of the casing 4, is an extension 5 of the casing adapted to provide a mounting for a rocker shaft 6, operatively connected to a drop arm 7 of the steering gear. The drop arm is secured to the shaft 6 by means of a nut 8, engaging 80 the threaded portion 9 on the end of the shaft 6. A lock washer 10 (Fig. 4) is mounted on the shaft between the arm 7 and the nut 8.

The cam 3, which is integral with or attached to the shaft 1, is mounted in the casing 4 so as to be rotatable about its longitudinal axis. At the ends of the casing, bearings 11 and 14 are provided in which fit bushings or sleeves 12, 15 respectively; 90 and the shaft 1 turns within sleeve 12 and its end or extension within sleeve 15, as shown in Fig. 2.

The cam 3 is similar in design to the cam described in my co-pending application referred to above, and comprises two opposed like cams 16, 17. The throw or pitch of the cams 13, 17 is approximately determined by the difference between the maximum and minimum diameters of the same, the cam 100 faces starting from the minimum diameter and rising or receding from the center throughout the circumference to the maximum diameter. It will be appreciated that with this opposed cam and rocker type of 105 steering gear, the total rocking movement of

the front wheels may be between 70° and 80°, and is effected by a steering wheel movement of something more than 360°.

One of the novel features of the invention is the single disk or roller disk employed, in contradistinction to the pair of rollers shown in my aforesaid application. The single roller disk is adapted to engage at diametrically opposite points the two opposed cams, and is operatively connected with the rocker shaft 6 for rocking said shaft to cause the desired movement of the front wheels for steering the automobile. The roller disk is mounted to turn about an axis disposed at an angle of 90° or thereabouts to the axis of the rocker shaft.

This single roller disk may assume any one of a number of different forms, each of which will function in the same manner and produce like results. The roller disk may be inclined at an angle to the longitudinal axis of the rocker shaft, or it may be substantially parallel with said axis.

As shown in Figs. 2, 3 and 4, the rocker shaft 6 has a recess machined near one end, in which is seated an anti-friction washer 18, on which is rotatably mounted a roller disk 19 by means of a pin 20. The recess in shaft 6, as Fig. 4 clearly shows, is plane, and makes an acute angle with the longitudinal axis of the shaft 6. The washer 18 has an inclined base 26 to seat upon the inclined bottom of the recess in the shaft; in other words, the washer is wedge-shaped in cross-section. Near the peripheries of the anti-friction washer 18 and the disk 19, and between the same, are formed the complementary sections of a track 21 (Fig. 2) constituting a ball race, in which are seated the ball bearings 22, so that the disk 19 will readily rotate on the anti-friction disk washer 18, when said disk is in engagement with the cam surfaces and operated thereby.

A slot 23 (Fig. 2) is formed in the inclined base 26 of the friction washer 18, whose outer face is substantially parallel to the longitudinal axis of the rocker shaft 6, as shown in Fig. 4. The slot 23 receives a semi-circular key 24 also mounted in a slot 24a located in the rocker shaft 6 for preventing lateral play of said key.

An adjusting screw 25, mounted in an internally threaded passage formed in the extension 13 in the longitudinal axis of the shaft 6, is adapted to engage the periphery of the anti-friction disk 18 and force the same towards the other end of the shaft, so that as the inclined base 26 of the anti-friction disk rides upon the inclined seat provided by the recess, the rotatable disk 19 is forced in close engagement with the opposed cam surfaces. The shaft 6 is cut away to permit the screw 25 to move inwardly for adjusting the roller disk 19. The key 24 serves to guide the disk 18 in its movement.

The object of this construction is to permit adjustment of the roller disk 19 and maintain the same in engagement with the opposed cam faces to take up any wear and prevent back lash.

In Figs. 2, 3 and 4, the bottom wall of the recess in the shaft 6 being inclined exactly like the base of the anti-friction washer 18, the roller disk 19 will be always kept parallel to the longitudinal axis of the shaft 6.

In Fig. 5, a slight modification of the adjusting means for the cam disk is shown. The anti-friction washer 18a has its base 26a and top portion parallel so that the thickness of the washer is uniform throughout and is seated in a recess in the rocker shaft 6 which is inclined relatively to the longitudinal axis of said shaft. A pin 27 which connects the rotatable disk 19 and the anti-friction washer 18a together, projects beyond the bottom face of the anti-friction disk and is seated within a socket formed in the rocker shaft 6, so that the anti-friction washer and roller disk are capable of independent rotation. The roller disk 19 will always be tilted at an angle to the longitudinal axis of the shaft 6, and the pin 27 prevents lateral play of said disk.

Instead of the screw 25 for adjusting the roller disk 19, I have provided screw threads 28 on a collar 29 which forms the bearing for the shaft end 13. These threads are adapted to be engaged by an internally threaded cap nut 30a. The extension 13 of the shaft 6 is in engagement with the inner surface of the cap 30a, and is provided with an internally threaded passage 32 adapted to be engaged by a stud 33, for locking the cap 30a to the shaft. The cap 30a may be hexagonal or of any angular form in order that it may be gripped by some suitable tool for turning the same, so that as the cap is moved inwardly, the shaft 6 will likewise be moved inwardly, and the roller disk 19 will be moved into closer engagement with the opposite cam surfaces for taking up any wear. A spring 34, secured to the casing 4, is adapted to engage one of the flat faces of the cap screw 30a to maintain it in position after an adjustment has been made.

Fig. 6 shows another modification of which my invention is susceptible. A rotatable disk 35 is adapted to engage the cam faces 16a and 17a of the opposed cams, but the contacting surface 36 of the disk is formed in the shape of a frustum of a cone, so that the inclined face of said rotatable disk will have a line engagement with the surfaces 16a and 17a of the opposed cams. The cam tracks 16a and 17a are inclined at a different angle than the tracks of the other cams disclosed, the inclination corresponding with the inclination of the frusto-conical portion 36 of the disk 35. A pin 38, rigidly mounted on the bottom of the roller

disk 35, is seated within a socket or bearing 39 formed in an enlargement of the rocker shaft 6, and at right angles to the longitudinal axis of the rocker shaft. The roller 5 disk 35 is moved towards or away from the cam faces of the cam by means of a screw or bolt 41, engaging the threads of a passage which is in alinement with the longitudinal axis of the stem 38. The outer end 10 of the screw or bolt 41 is provided with a head 42 to be gripped by some suitable tool for turning the screw 41. A lock nut 43 engages the threads of the screw 41 for locking the screw in position on the rocker 15 shaft 6.

Fig. 7 discloses still another modification of the rotatable disk, in the form of a flat disk 44 having a stem 45, secured centrally of the disk and at right angles to the plane 20 of said disk, and seated within a socket 46 passing entirely through the rocker shaft 6. The rotatable disk in this case has its two faces parallel. The adjustment means of Fig. 6 may be conveniently employed with 25 the disk of Fig. 7.

Referring again to Figs. 1 to 5, inclusive, the extension 5 of the casing 4 is sectionally formed so that cap 48 may be removed when the bolts 49 have been taken out, in order 30 that the rocker shaft and some of its connected parts may be exposed.

Longitudinally of the shaft 6, there is provided a bore or passage 50, (Fig. 4) having a port 51 at right angles to the passage 35 50, said port communicating with a chamber 52 in the extension 5 for permitting lubricant to pass from the bore 50 to said chamber 52. The end of the passage 50 is internally threaded to hold a grease cup 53 40 closing the passage.

A plug 54, mounted in an internally threaded boss 55, is adapted to close an opening 56 (Fig. 2) which leads into the interior of the casing, and by which lubricant is forced into the same.

As shown in Fig. 4, a bracket 57 embracing the extension 5 of the casing is mounted on the automobile frame for securing the casing in position.

In all the described embodiments of the invention, the rotatable disk, by reason of its engagement with the opposed cams 16 and 17, is oscillated through an arc of substantially 80°, so that as the shaft 6 is 50 rocked by the rotatable disk, the drop arm 7 of the steering gear connected to a reach rod 47 (Fig. 1) is oscillated through an arc of 80°, while the cams are being turned through very nearly two revolutions. For 55 practical purposes, the cam itself may be turned through at least one and one half revolutions.

While the invention has been described with particular reference to steering mechanism, the invention has a much broader

aspect and may be applied to other mechanical devices where it is desired to change a rotary motion to a rocking motion.

What is claimed is:—

1. The combination with a rotatable 70 shaft, a pair of opposed like cams mounted thereon, a rocker shaft at one side of the cams arranged at an angle to said rotatable shaft, and a rotatable disk carried by the rocker shaft at the same side of the cams as 75 the latter and having its face engaging both the cams for rocking the rocker shaft.

2. The combination with a rotatable shaft, a pair of cams mounted thereon, a rocker shaft arranged at an angle to the 80 rotatable shaft, and a rotatable disk mounted on the rocker shaft and having its flat face engaging both cams for rocking the rocker shaft.

3. The combination with a rotatable 85 shaft, a pair of opposed cams mounted thereon, a rocker shaft arranged at an angle to the said shaft, a rotatable disk operatively mounted between the rocker shaft and the cams and having its face engaging 90 both the cams, and means for adjusting the disk toward the cams for taking up backlash occasioned by wear of the parts.

4. The combination with a rotatable 95 shaft, a pair of opposed cams mounted thereon, a rocker shaft mounted substantially at right angles to said shaft and spaced therefrom, and a single rotatable disk directly mounted on the rocker shaft in the space between the latter and the said cams and having its substantially flat face engaged at diametrically opposite points by the cams for rocking the rocker shaft.

5. A steering gear for motor vehicles, comprising a steering column, a pair of opposed cams mounted on the steering column, a rocker shaft, and a circular disk rotatably mounted on the rocker shaft and engaged at diametrically opposite points on the same flat face by both cams for rocking the shaft.

6. A steering gear for motor vehicles comprising a steering column, a pair of opposed cams secured to the column, a rocker shaft, a rotatable disk mounted on the shaft and having its face engaging both cams, and means for adjusting the disk toward the cams to take up wear.

7. A steering gear for motor vehicles, comprising a steering column, a pair of opposed volute cam tracks mounted on the steering column, a rocker shaft, rotatable means on the rocker shaft engaged at diametrically opposite points by the cam tracks for rocking the shaft when the steering column is turned, and an adjustable means for maintaining the cam tracks and the rotatable means in engagement.

8. A steering gear for motor vehicles, comprising a steering column, a pair of opposed cams mounted on the steering column,

a rocker shaft mounted at an angle to the steering column, a rotatably mounted disk engaged by both cams for rocking the shaft, and means mounted on the shaft to move the disk toward the cams to take up wear.

9. A steering gear comprising a steering column, a cam mounted thereon having two opposed cam tracks each comprising a cam surface greater than 360° but less than 720° , 10 a flat circular disk rotatably mounted adjacent the cam and engaging both cam tracks on the same face but at diametrically opposite points, and a shaft connected to and rocked by the disk, said shaft being operatively connected to the steering wheels to move the latter when the steering column is rotated.

10. A steering gear comprising a steering column, a cam mounted thereon having two opposed cam tracks each comprising a cam surface greater than 360° , a flat circular disk rotatably mounted adjacent the cam and engaging both cam tracks on the same face but at diametrically opposite points, a 25 shaft connected to and rocked by the disk, said shaft being operatively connected to the steering wheels to move the latter when the steering column is rotated, and means for moving the rotatable disk bodily toward both cam surfaces and for maintaining engagement therewith, whereby backlash is 30 taken up.

11. A steering gear comprising a steering column, a cam mounted thereon having two opposed cam tracks, a rocker shaft supported to turn on an axis at right angles to the axis of the steering column; a disk mounted on the rocker shaft to rotate on an axis at right angles to the axis of the rocker 40 shaft and held in engagement with both cam tracks, and means for moving the disk bodily into closer contact with said cam tracks, whereby backlash in the gear may be taken up.

45 12. A steering gear comprising a steering column, a cam mounted thereon, a rocker shaft supported near the cam, a disk rotatably carried by the rocker shaft and engaging the cam whereby turning of the steering column rocks the rocker shaft, said disk being supported by anti-friction means, and means for moving the anti-friction support for the disk, and with it the disk itself in a direction such that the disk is forced 50 into closer contact with the cam.

13. A steering gear comprising a steering column, a cam mounted thereon, a rocker shaft supported near the cam, a disk rotatably carried by the rocker shaft and engaging the cam whereby turning of the steering column rocks the rocker shaft, said disk being supported by anti-friction means, and means for moving the anti-friction support for the disk, and with it the disk itself 55 in a direction such that the disk is forced

into closer contact with the cam, said means comprising a screw which bears against the anti-friction means, the rocker shaft having a recess with an inclined wall seating the anti-friction means, and the anti-friction 70 means having an inclined base to fit the recess and slide therein when the adjustment screw is turned.

14. In steering mechanism of the class described, a rotatable steering shaft; two oppositely arranged cam members carried by said shaft and located adjacent the lower end thereof; an oscillating shaft located adjacent said cams and extending transverse to said steering shaft; a bearing member carried by said oscillating shaft and with which both the cam members aforesaid engage, and which bearing member is located between the axes of said steering shaft and said oscillating shaft; and means 80 for moving said bearing member transverse to said oscillating shaft and toward and from said cam members.

15. In steering mechanism of the class described, a rotatable steering shaft; two oppositely arranged cam members carried by said shaft and located adjacent the lower end thereof; an oscillating shaft adjacent said cams and extending transverse to said steering shaft and which shaft is provided with a recess adjacent said cam members; a bearing member located within said recess and with which both the cam members aforesaid engage; and means for adjusting said bearing member toward and from said cam members.

16. In steering mechanism of the class described, a rotatable steering shaft; two oppositely arranged cam members carried by said shaft and located adjacent the lower end thereof; an oscillating shaft located adjacent said cams and extending transverse to said steering shaft and which shaft is enlarged and provided with a cylindrical recess adjacent said cam members; a cylindrical bearing member located within said recess and with which the cam members aforesaid engage; and a set screw carried by said oscillating shaft and in operative engagement with said bearing member.

110 17. In steering mechanism of the class described, a rotatable steering shaft; two oppositely arranged cam members carried by said shaft and located adjacent the lower end thereof; an oscillating shaft located adjacent said cams and extending transverse to said steering shaft, and which shaft is provided with a bearing surface which is inclined relative to the axis thereof and against which surface both the cams aforesaid bear; and means for moving said oscillating shaft along its axis to thereby adjust said bearing surface relative to said cams.

120 18. In steering mechanism of the class

- described, a rotatable steering shaft; two oppositely arranged cam members carried by said shaft and located adjacent the lower end thereof; an oscillating shaft located adjacent said cams and extending transverse to said steering shaft; a rotatable disc carried by said oscillating shaft and against which both the cams aforesaid bear, and the surface of which disc is inclined relative to the axis of said oscillating shaft; and means for moving said oscillating shaft along its axis to thereby adjust said bearing disc relative to said cam. 19. In a steering mechanism of the class described, a rotatable steering shaft; two oppositely arranged cam members carried by said shaft and located adjacent the lower end thereof; an oscillating shaft located adjacent said cams and extending transverse to said steering shaft; a bearing plate carried by said oscillating shaft and the under surface of which is arranged at an angle relative to the axis of said shaft, and against which bearing plate both the cams aforesaid bear; and means for moving said oscillating shaft along its axis to thereby adjust the bearing surface thereof relative to said cams. 20. In steering mechanism of the class described, a rotatable steering shaft; two oppositely arranged cam members carried by said shaft and located adjacent the lower end thereof; an oscillating shaft located adjacent said cams and extending transverse to said steering shaft; means carried by said oscillating shaft and inclined relative to the axis thereof and engaged by both the cams aforesaid, and through which motion is communicated to said oscillating shaft as said steering wheel is rotated; and means for moving said oscillating shaft along its axis to thereby adjust the bearing surface thereof relative to said cams.

In testimony, that I claim the foregoing as my own, I have hereto affixed my signature.

HENRY MARLES.
